US00D914198S

(12) **United States Design Patent** (10) **Patent No.:** **US D914,198 S**
Li et al. (45) **Date of Patent:** **** Mar. 23, 2021**

(54) **HANDHELD SMART ORAL IRRIGATOR**

(71) Applicants: **Jinfeng Li**, Hubei (CN); **Gang Wang**, Hunan (CN); **Qing Zhang**, Anhui (CN); **Xinquan Liu**, Sichuan (CN); **Xiaowen Liu**, Hunan (CN)

(72) Inventors: **Jinfeng Li**, Hubei (CN); **Gang Wang**, Hunan (CN); **Qing Zhang**, Anhui (CN); **Xinquan Liu**, Sichuan (CN); **Xiaowen Liu**, Hunan (CN)

(73) Assignee: **FLYCAT ELECTRICAL CO., LTD.**, Guangdong (CN)

(**) Term: **15 Years**

(21) Appl. No.: **29/665,927**

(22) Filed: **Oct. 8, 2018**

(51) LOC (13) Cl. **24-02**

(52) U.S. Cl.

USPC **D24/111**

(58) **Field of Classification Search**

USPC D24/107-108, 111, 169, 185-186;
D4/102-102, 109-111, 138

CPC A61M 5/142; A61M 2205/502; A61M 5/1452; A61M 2205/505

(57) **CLAIM**

The ornamental design for a handheld smart oral irrigator, as shown and described.

DESCRIPTION

FIG. 1 is a perspective view for a handheld smart oral irrigator showing our new design;

FIG. 2 is a front side view thereof;

FIG. 3 is a rear side view thereof;

FIG. 4 is a right side view thereof;

FIG. 5 is a left side view thereof;

FIG. 6 is a bottom plan view thereof; and,

FIG. 7 is a top plan view thereof.

The broken lines depict features of the handheld smart oral irrigator that form no part of the claimed design.

1 Claim, 7 Drawing Sheets
